(57) CLAIM

The ornamental design for a combination disk and straw, as shown and described.

DESCRIPTION

FIG. 1 is a top, front, left perspective view of a combination disk and straw, showing my new design;

FIG. 2 is a left side elevation view thereof;

FIG. 3 is a right side elevation view thereof;

FIG. 4 is a front elevational view thereof;

FIG. 5 is a rear elevational view thereof;

FIG. 6 is a top plan view thereof; and,

FIG. 7 is a bottom plan view thereof.

The equal-length broken lines in the drawings depict portions of the combination disk and straw that form no part of the claimed design.
